UNITED STATES PATENT OFFICE

CHARLES S. TURNER, OF DETROIT, MICHIGAN

SINGLE HEADER MULTIPLE-PASS SUPERHEATER

Application filed December 13, 1928. Serial No. 325,728.

This invention relates to boiler superheaters, and has for its object improvements particularly directed to a single header multiple-pass type of superheaters. The principal objections to the constructions of this general type heretofore used have been that the tubes connecting the steam drum with the discharge header have fared unequally in the matter of the distribution of the steam pressure intended to be transmitted through them. In other words, certain ones of the series of pipes, more advantageously positioned relatively to the point of entrance of the steam have drawn and transmitted a greater amount of steam pressure than others less advantageously located. As long as the method of attaching the inlet and outlet ends of the steam pipes in a row along the wall of the steam drum is followed, there seems to be no adequate way of overcoming this trouble, which my experience leads me to believe is due to the lateral motion of the steam along the axis of the header taking place in the headers, rather than in the tubes. Furthermore, in an effort to increase the steam-treating capacity or linear extent of the individual tubing sections, resort has been had to multiple or interior loopings thereof, that is, locating several of the constituent sections of a single tubing unit within the same plane as viewed transversely of the steam drum. This has, however, proved highly objectionable in practice, in that in case a leak occurs in any of these interior curvatures of the pipe, it is necessary to disassemble an inconveniently large proportion of the uninjured units on either side in order to afford access to the damaged pipe. Both of these objections I have overcome in the improved construction herein illustrated in the figures of drawings, wherein:

Figure 1 is an elevational view of the simplest embodiment of my improved construction, namely a plural connection between two steam drums or headers with the pipes spacedly arranged lengthwise of the axis thereof.

Figure 2 is a sectional plan view thereof taken along the line 2-2 of Figure 1 and

looking in the direction of the arrows there shown.

Figure 3 is a more or less diagrammatic showing taken generally along the line 3-3 of Figure 1, to enable the tracing of the course of the steam through a single series of pipe and header sections from the steam drum to the discharge header.

Figure 4 is a more or less diagrammatic view of a consolidated portion of a single pipe of the apparatus illustrated in Figure 1, designed to bring out the course of the steam therethrough from the steam drum to the discharge header.

Figure 5 is an elevational view similar to Figure 1, embodying a slightly variant contouring of the pipe sections.

Figure 6 is a plan view of this modified form shown in Figure 5, taken from above.

Figure 7 is an elevational and partly diagrammatic sectional view of a single series of pipe curvatures in the form of apparatus shown in Figure 5.

Figure 8, which is a perspective, is designed to bring out the sequence and relation of the constituent sections of a single pipe unit from steam drum to header in the form of apparatus shown in Figure 5.

Figure 9 is a side elevational view of this modified form included within the superheater space of a steam boiler, embodying a plurality of sections taken one within the other, this view being taken from a position looking lengthwise of the steam drum, in the same manner that Figure 3 is illustrative of a single unit of the type of steam piping units employed in Figure 1.

It is my belief, based on my experience with various kinds of superheating apparatus, that a large proportion of the operative shortcomings of such equipment in the past has been due to undue lateral or lengthwise travel of the steam in the receiving drum or header, caused in turn by an inequality of the feed into it of the steam from the steam drum. This I propose to remedy, as brought out in Figure 1 by providing a single feeding pipe or series of pipes as B, leading from the steam source such as an ordinary steam drum A, to laterally located positions of entrance into the

lower header Z, extending along a line parallel with the axis thereof, and with oppositely positioned discharge pipes, one outlet tube being directly opposite each inlet tube (this feature is clearly shown in Figure 2) 5 employed in similar number to the pipes A for leading the steam into the discharge header. For small capacity installations this simple arrangement is in many cases adequate 10 for accomplishing the avoidance of inequalities in the distribution of steam in such an apparatus. But for large power plant uses an elaboration or extension of this basic idea of avoiding cross or conflicting lines of steam 15 travel becomes advisable, and my ideas as to one form of such an apparatus are embodied in Figures 1, 3, and 9, wherein A indicates an ordinary steam drum supported in any desired manner as between uprights A', the ordinary water level whereof is indicated with 20 particular clearness in Figure 3, as well as by the dotted line a in Figure 1. Above this level, so as to lead into the interior of the steam drum, at a point definitely thereabove, 25 are tapped a series of pipe sections B, each of which leads downwardly therefrom in substantially parallel relation to connection with the header Z, similarly leading into the upper portion thereof as at b in Figures 1 and 3. 30 It will be noted that in the construction illustrated in Figure 1 these several connecting pipes B occupy illustratively only about one-fourth of the linear extent of said header Z. Just to the right of this series of pipes is 35 positioned, in the header Z, a diaphragm L which confines the steam transmitted thereto through the pipes B to the corresponding section C of this header, except as the escape and further travel of the steam therefrom is made possible through the connection with the other side of the top portion of the lower drum of the ends of a series of U-shaped pipe sections D, of the same number as those composing the series B just mentioned, each one of the inlet tubes B opening 40 into its chamber opposite a corresponding outlet tube of the series D. Each one of the outlet tubes D is directly opposite a corresponding inlet tube of the series B. These 45 U-shaped pipe sections extend over the lower drum section C and angularly with reference to the lengthwise axis thereof to inlet connection with the next diaphragm-bounded lower drum section E whose top portion they 50 enter in the same manner as did the pipes B into the drum section C. Similarly from the other side of the top portion of the lower header section or header E another set of U-shaped pipe sections, as F, leads therefrom, each outlet tube being directly opposite 55 a corresponding inlet tube, and extends outwardly and upwardly in a loop for the absorption of heat, similarly to section D; its course being parallel thereto, the tubes returning to the next section G of the header 60

which is spaced from the section E, by the diaphragm M. From the far side of the upper portion of the header Z, as viewed in Figure 1, and from the upper side thereof as viewed in Figure 2, another series of U-shaped pipe sections as H leads, again arching over the header Z parallel to the tubes in sections D and F, and returning similarly to connection therewith in its chamber I which is spaced from the next previous section G by the diaphragm N. Then from the far side of the header Z as viewed in Figure 1, and the upper side thereof as viewed in Figure 2, another series of pipe sections J extends from the chamber I of the lower drum Z each outlet being opposite the corresponding inlet to connection with the discharge header K, which for clearness of illustration is shown in Figure 1 as positioned just below the steam drum A. Any number of such pipe sections and diaphragm-isolated header units may be employed, according to the designed capacity of the particular apparatus. In each case it will be noted that two highly desirable results are secured: the limitation 90 of the possible lateral travel of the steam lengthwise of the header Z, due to the presence of the several diaphragms or partitions L, M and N, and the assurance that the steam, on emerging from any one of the pipes of series B, for example, into the header C, finds ready and directly oppositely positioned egress means through the correspondingly positioned outlet pipes of the U-shaped series D, thus avoiding a possible crossing of the steam flowage lines or an undue bleeding of 95 some of the pipes of that series by one or more of its companion pipes, such as would result if no restriction were placed upon the degree of lateral travel of the steam within 100 the drum as it emerges from the several pipes of the series B. This guiding restriction or limitation upon the possible paths of travel of the steam prevails both as to the principle and the structure employed to effect it 105 throughout the several diaphragm-formed chambers and their appurtenant and connecting U-shaped pipe sections.

I thus provide in either of the forms of construction illustrated in Figures 1 to 3, or in either of the modified forms of construction hereinafter to be discussed, a grouping of the pipe sections within a relatively limited extent at several points along the length of the header Z, so that even though there be a slight variation in the steam pressure transmitted to the several component units of the first pipe series B, any inequality thereof is confined and redistributed within the first section C, so that upon egress of the steam therefrom into the first series of U-shaped pipes D, the pressure in one is much more nearly that in the others than may have been the case if some inequality prevailed through the various pipe sections of the se- 110

ries B. This equalization is continued in the direction of further progress toward uniformity during the transmission of steam from the header section E and through the 5 pipes of the series F into the next header section G, and so on, so that throughout the riser pipe system an even distribution of the steam pressure among the constituent pipe sections has been maintained.

10 In the modified form of piping sections illustrated in Figures 6, 7 and 8, the same principles have been followed as regards isolation of the steam in the several sections of the header I and the opposite positioning of the 15 inlet and outlet pipes of each section. In this form steam entering from the drum P proceeds through the pipe sections of series Q into the first diaphragm-isolated section R of the header I, thence through the riser tubes of the 20 series S into the next section T of the header I, thence through the next riser sections U to the third section V of the header I, thence through the next series of riser section tubes W to the last diaphragm-isolated section X of the header, and thence through the riser pipes 25 Y to the discharge header O. This is brought out diagrammatically as to a single pipe of each of the series described in Figure 7, the 30 several diaphragms or partitions shown in that figure as well as in Figures 6 and 8 being designated as L', M' and N', since they perform the same subdividing function as to the lower drum Z as a whole as do the diaphragms L, M, and N in Figures 1 and 2.

35 In Figure 9 I have illustrated a modified form of construction adapted especially to overcome the second one of the objections to previous apparatus noted in the introductory 40 paragraph hereof, to-wit, the provision within the same vertical plane of an added or supplemental number of component pipe sections for each of the riser units which go to make up a series of pipes such as D, F, and H in Figure 1, in order to provide a greater total 45 of piping surface between the header sections. It will be obvious that the plane of any one of these sections thus constituted will as a whole lie at a slightly acute or obtuse angle 50 relatively to either the lengthwise axis of the steam drums A or Z, or to the plane of Figure 1, for example, because of each of the U-shaped riser pipe sections therein illustrated extending angularly from one side of, for 55 example, the header section C, to the other side of the next header section as E. Thus the element designated P' in this figure corresponds in position and function with the drum P of Figure 6, and directly behind it, as 60 viewed in this figure would be located a discharge header corresponding to element O in Figure 6; the pipe sections B', B² and B³ would correspond to one pipe of the riser section Q of Figure 6; and the lower drum C' 65 would correspond with the corresponding structural and functional element I therein.

But in order to provide additional linear extent per riser section unit, without involving undue height of the apparatus as a whole, each group of the first of the pipe series corresponding, for example, to the series B of 70 Figure 1, has three egress sections as B', B² and B³ curved in position for the passage of the steam through them and their corresponding header, as C' before it can go further and into the egress pipes D' and D² corresponding to the series D of Figure 1; each of these supplemental pipe sections being individually removable in case of the bursting or leakage of any one, it may be removed or repaired with a minimum of effort and displacement of adjoining parts. 75

What I claim is:

1. In a boiler superheater, in combination with a steam drum and a series of discharge pipes leading therefrom, a plurally chambered superheater header into one section of which said discharge pipes lead in a direction substantially perpendicular to the lengthwise axis thereof, a plurality of series of generally U-shaped pipe sections connecting 85 each of the chambers in the header with the chamber adjoining, the tubes in each case leading into and from opposite sides of the several chambers in substantial lateral alignment with each other. 90

2. In a boiler superheater, the combination with a steam drum and a series of discharge pipes leading therefrom, of a plurally chambered header into a side of one chamber of which said discharge pipes lead, a plurality 100 of series of U-shaped tube sections each member of each series of which leads from connection with one of the chambers in said header to connection with the adjoining chamber, the several tubes connecting with each chamber in oppositely disposed portions thereof, and the inlet and outlet tubes being substantially laterally aligned in planes normal to the axis of the header. 105

3. In a boiler superheater, in combination 110 with a plurally chambered header, tubes connecting the chambers in series and so arranged that their inlets lead into one side of each of the intermediate of said chambers and their outlets therefrom are arranged in substantial 115 alignment with each inlet in a plane normal to the axis of the header.

In testimony whereof I sign this specification.

CHARLES S. TURNER. 120
